(57) **CLAIM**

I claim the ornamental design for a cap for cylindrical container, as shown and described.

DESCRIPTION

FIG. 1 is a perspective view of a cap for cylindrical container; FIG. 2 is a top plan view of the cap shown in FIG. 1;

FIG. 3 is a right and left side, elevational plan view of the cap shown in FIGS. 1 and 2, the right and left side views being mirror images of each other;

FIG. 4 is a perspective view of another embodiment of a cap for cylindrical container;

FIG. 5 is a top plan view of the cap shown in FIG. 4; and, FIG. 6 is a right and left side, elevational plan view of the cap shown in FIGS. 4 and 5, the right and left side views being mirror images of each other.
